SNAP ACTING ELECTRIC SWITCH

Orion Ottis Oaks, Summit, N. J., assignor, by
mesne assignments, to Thermal Liquids, Inc.,
New York, N. Y., a corporation of Delaware

Application January 26, 1949, Serial No. 72,835

6 Claims. (CL 200—140)

1

This invention relates to snap acting electric switches and more particularly to such switches of the mercury tube type actuated by a thermostatic element.

Heretofore various types of mercury tube type snap acting switches have been proposed for use in various electrical circuits and many of these have been actuated by thermostatic means. Many of these switches are efficient and of positive operation but others are lacking in simplicity of structure and reliability. The present invention provides a novel snap acting switch of the mercury tube type actuated by a temperature responsive expansible and collapsible corrugated metallic vessel which is of very simple construction and of reliable and positive action.

It is accordingly an object of the present invention to provide a novel switch of this type which is of simple construction and of positive and reliable action.

Another object of the present invention is to provide such a switch which can be actuated by a suitable thermostatic element.

Another object of the present invention is to provide such a switch which is cheap and easy to manufacture; and readily and easily adjustable.

Other and further objects of the present invention will appear from the following description.

My novel switch is capable of various mechanical embodiments one of which is shown in the accompanying drawings and is described hereinafter to illustrate the invention. This illustrative embodiment of my invention should in no way be construed as defining or limiting the same and reference should be had to the appended claims to determine the scope of this invention.

In the accompanying drawings, in which like reference characters indicate like parts,

Fig. 1 is a side view, partly in section, of an illustrative embodiment of my invention showing the relative position of the several parts thereof when the thermostatic element is in collapsed position; and

Fig. 2 is an end view of the embodiment of my invention as seen from the right in Fig. 1.

Referring now to the drawing, my novel thermostatically actuated switch is seen to comprise a base element 10, preferably circular in shape and provided with threads 11 so that the same may be suitably secured in the casing (not shown) of an element containing the expansible and collapsible corrugated metallic element 12 which is subject to the temperatures to be controlled. Base 10 is provided with a hollow upstanding ex-

2

tension 13 closed at end 14 and apertured at 15. Plug 16 is mounted for reciprocation within hollow extension 13 and is internally threaded at 17 to receive one end of connecting rod 18. A lock nut 19 is provided to prevent rotation between connecting rod 18 and plug 16. Connecting rod 18 extends through aperture 15 and is surrounded by spring 20 which abuts end 14 and lock nut 19 to force rod 18 and plug 16 downward as seen in Fig. 1. Thermostatic vessel 12 is provided with an actuating post 21 which is of enlarged diameter at 22 to slide in hollow extension 13 and to engage plug 16.

Rod 18 may be provided with a suitable aperture 23 through which a tool may be inserted to hold rod 18 for purposes of adjustment. The upper end of rod 18 is threaded at 24 to receive adjusting housing 25, lock nut 26 being provided to prevent rotation between rod 18 and housing 25. Housing 25 is axially recessed at its upper end at 27 and diametrically opposed slots 28 open axially into aperture 27. A link 29 is mounted for reciprocation in recess 27 and is provided at its lower end with a pivot 30 extending through both slots 28.

Support 31 is suitably secured to base 10 as by screws 32 and extends upwardly to a point above the upper end of housing 25 when housing 25 is in its lowest position. Bell crank 33 is pivoted to support 31 and 34 and is pivoted at 35 to link 29. Mounting clip 36 is suitably secured to bell crank 33 and is provided with clips 37 surrounding and holding a conventional mercury tube electric switch 38. Switch 38 is provided with electrical leads 39 and 40.

An L-shaped support bracket 41 is suitably secured to base 10 as by bolts 42 and carries a pivot pin 43. Rocking link 44 is pivotally mounted on pin 43 and is held thereon by cotter key 45. A pair of snap links 46 are pivotally mounted on rocking link 44 at 47 and are also pivotally mounted on pivot 30. A second pair of snap links 48 are pivotally mounted on support 31 at 49 and are also pivotally mounted on pin 30. One of arms 46 is provided with spring support 50 adjacent pivot 47 and the corresponding arm of arms 48 is provided with a spring support 51 adjacent pivot 49. A spring 52 is tensioned between spring supports 50 and 51.

With the embodiment of my invention set up as above described assume that the several elements thereof are positioned as shown in Fig. 1 and switch 38 is in closed position. Upon a rise in temperature thermostatic vessel 12 will expand and post 21 will slide plug 16 and rod 18 upwardly in extension 13 against the action of spring 20 and pivot 30 will be moved upwardly with

links 46 and 48 rotating thereon. Upward movement of pivot 38 and rotation of links 46 and 48 rotates link 44 to the right, as seen in Fig. 1, and further tensions spring 52. Spring 52 continues to stretch until pivot 38 passes through its center line. Upward movement of pivot 38 moves link 28 upwardly and rotates bell crank 33 about pivot 34 rotating switch 38 in a counterclockwise direction. When pivot 38 passes the center line of spring 52 spring 52 contracts rotating link 44 to the left and snapping link 28 into its extreme upward position, pivot 38 riding upward in slots 23, which in turn rotates bell crank 33 in a counterclockwise direction and snaps switch 38 from "on" position to "off" position.

When thermostat 12 is cooled it collapses withdrawing post 21 from plug 16 and spring 20 moves plug 16 and rod 18 downwardly. Downward movement of rod 18 moves pivot 38 downwardly and rotates bell crank 33 and switch 38 in a clockwise direction as seen in Fig. 1. This downward movement continues until pivot 38 passes the center line of spring 52 at which time spring 52, which has been tensioned by the initial downward movement of pivot 38, retracts and snaps pivot 38 and link 28 to its lowest position in housing 25 rotating bell crank 33 and switch 38 rapidly from "off" position to "on" position.

It will now be apparent that by the present invention I have provided a novel thermostatically actuated snap action mercury tube type electric switch which is of positive and reliable operation; which is cheap and easy to manufacture; which is of simple construction; and which is of easy adjustment.

Changes to or modifications of the above described illustrative embodiment of my invention may now occur to those skilled in the art without departing from my inventive concept. To determine the scope of this invention reference should therefore be had to the appended claims.

What is claimed is:

1. In a snap acting switch, a base, a hollow extension for said base, a connecting rod mounted for reciprocation in said hollow extension, resilient means biasing said connecting rod toward said base, a thermostatic element operating through said base and engaging said rod, an axially bored and laterally slotted member adjustably mounted on said rod, a slide link mounted for reciprocation in said axially bored member, a pivot pin carried by said slide link extending through said slots, an upwardly extending support secured to said base, an upwardly extending rocking link pivoted to said base, a pair of snap links pivotally mounted on said support and pivotally engaging said pin, a second pair of snap links pivotally mounted on said rocking link and pivotally engaging said pin, a spring tensioned between the pivots of said pairs of snap links at said support and at said rocking link, a bell crank pivotally mounted on said support and pivotally engaging said slide link and a tube type mercury switch carried by said bell crank.

2. In a snap acting switch, a base, a connecting rod mounted for reciprocation in said base, resilient means biasing said rod toward said base, a thermostat operatively engaging said rod, an axially slotted extension for said rod, a pin sliding in said slot, a slide link mounted on said pin, an upwardly extending post mounted on said base, an upwardly extending rocking link pivoted to said base, a link pivotally engaging 75

said rocking link and said pin, a second link pivotally engaging said post and said pin, resilient means connecting the pivots of said links at said post and at said rocking link, a bell crank pivoted on said post and pivotally engaging said slide link and an electric switch operated by said rocker arm.

3. In a snap acting switch, a base, a rod slidably mounted in said base, thermostatic means for sliding said rod, resilient means biasing said rod toward said base, means providing an axial slot carried by said rod, a pin slidably mounted in said slot, a sliding link carried by said pin, a post secured to said base and spaced from and extending parallel to said rod, a rocking link pivoted to said base and spaced from said rod, linkage pivoted on said rocking link and pivotally engaging said pin, linkage pivoted on said post and pivotally engaging said pin, tensioned resilient means connecting the pivots of said linkage at said post and at said rocking link and an electric switch actuated by the movement of said sliding link.

4. In a snap acting switch, a base, a hollow extension for said base, a connecting rod mounted for reciprocation in said hollow extension, resilient means biasing said connecting rod toward said base, an axially bored and laterally slotted member adjustably mounted on said rod, a slide link mounted for reciprocation in said axially bored member, a pivot pin carried by said slide link extending through said slots, an upwardly extending support secured to said base, an upwardly extending rocking link pivoted to said base, a pair of snap links pivotally mounted on said support and pivotally engaging said pin, a second pair of snap links pivotally mounted on said rocking link and pivotally engaging said pin, a spring tensioned between the pivots of said pairs of snap links at said support and at said rocking link, and a switch operating a bell crank pivotally mounted on said support and pivotally engaging said slide link.

5. In a snap acting switch, a base, a connecting rod mounted for reciprocation in said base, resilient means biasing said rod toward said base, an axially slotted extension for said rod, a pin sliding in said slot, a slide link mounted on said pin, an upwardly extending post mounted on said base, an upwardly extending rocking link pivoted to said base, a link pivotally engaging said rocking link and said pin, a second link pivotally engaging said post and said pin, resilient means connecting the pivots of said links at said post and at said rocking link, and a switch operating a bell crank pivoted on said post and pivotally engaging said slide link.

6. In a snap acting switch, a base, a rod slidably mounted in said base, resilient means biasing said rod toward said base, means providing an axial slot carried by said rod, a pin slidably mounted in said slot, a switch actuating sliding link carried by said pin, a post secured to said base and spaced from and extending parallel to said rod, a rocking link pivoted to said base and spaced from said rod, linkage pivoted on said rocking link and pivotally engaging said pin, linkage pivoted on said post and pivotally engaging said pin, and tensioned resilient means connecting the pivots of said linkage at said post and at said rocking link.
